UNITED STATES PATENT OFFICE.

LAUCHLIN D. BYRD, OF HILLSDALE, MISSISSIPPI.

TURPENTINE-RECEPTACLE.

SPECIFICATION forming part of Letters Patent No. 786,950, dated April 11, 1905.

Application filed November 11, 1904. Serial No. 232,367.

To all whom it may concern:

Be it known that I, LAUCHLIN D. BYRD, a citizen of the United States, residing at Hillsdale, in the county of Pearl River and State 5 of Mississippi, have invented new and useful Improvements in Turpentine-Receptacles, of which the following is a specification.

My invention pertains to receptacles designed to be attached to pine-trees with a view of catching crude turpentine as the same exudes from the trees; and it has for its object to provide an inexpensive but very durable receptacle adapted to be attached to a pine-tree in such manner that no cutting of the tree is necessary except the ordinary well-known chipping, this being advantageous, inasmuch as the chipping does not tend to deaden a tree or spoil the pores thereof, as does deep cutting of the tree.

With the foregoing in mind the invention will be fully understood from the following description and claims when taken in connection with the accompanying drawings, forming part of this specification, in which—

Figure 1 is a perspective view illustrating the receptacle constituting the present and preferred embodiment of my invention in its proper operative position on a pine-tree. Fig. 2 is an enlarged perspective view of the receptacle removed, and Fig. 3 is a vertical central section of the receptacle.

Similar letters of reference designate corresponding parts in all of the views of the drawings.

The receptacle illustrated in the drawings is formed of a single piece of sheet metal and comprises a back wall A, a front wall B, formed by lapping the lower portions of the piece of sheet metal and connecting the same together, as indicated by C, and side walls D, which converge downwardly to a point E. The back wall extends a considerable distance above the front and side walls and is provided in the vertical center of its upper portion

with an aperture α and is also provided with wings F. These latter are formed by shaping the upper end of the back wall A so that the same describes an obtuse angle, the apex of which is disposed above and adjacent to the aperture α .

In the practical use of my novel receptacle the same is applied after the manner shown in Fig. 1—that is to say, the back wall A is arranged against a tree and the wings F are adjusted under a peak—*i. e.*, a strip of bark 55 at the lower end of a chipped face. After the receptacle is fastened in the position stated through the medium of a nail or the like driven through the aperture α chipping of the tree is continued upward from the strip of 60 bark in order to enable the turpentine to flow into the receptacle over the wings F. As will be readily observed by reference to Fig. 1, the inner edges of the wings F snugly receive the peak or strip of bark on a pine-tree, 65 and hence the wings are enabled to assure the turpentine passing into the receptacle and not back of the receptacle.

In virtue of the construction of my novel receptacle the lifetime of the tree upon which 70 it is used is materially prolonged, inasmuch as the mere chipping of the face does not tend to kill a tree or injure the pores thereof or weaken the tree to such an extent as to render the same liable to fall. The receptacle is 75 also advantageous, inasmuch as when it is moved up each season—*i. e.*, from a point below one chipped face to a point below a new chipped face to be provided above the first-mentioned chipped face—the turpentine which 80 it will catch will be the better quality, known as “virgin dip.”

Having described my invention, what I claim, and desire to secure by Letters Patent, is—

A turpentine - receptacle converging to a point at its lower end, and formed of a single sheet of metal having one horizontal edge bent upward from its central point, the two portions being lapped and connected together, and having its remaining part terminating in wings, the inner edges of which are disposed at an angle to each other.

In testimony whereof I have hereunto set my hand in presence of two subscribing witnesses.

LAUCHLIN D. BYRD.
